UNITED STATES PATENT OFFICE.

JOHN S. FINCH, OF BRIDGEPORT, CONNECTICUT, ASSIGNOR TO THE SINGER MANUFACTURING COMPANY, A CORPORATION OF NEW JERSEY.

BUTTON-STAPLING MACHINE.

1,364,264.

Specification of Letters Patent.

Patented Jan. 4, 1921.

Application filed December 18, 1917. Serial No. 207,675.

To all whom it may concern:

Be it known that I, JOHN S. FINCH, a citizen of the United States, residing at Bridgeport, in the county of Fairfield and 5 State of Connecticut, have invented certain new and useful Improvements in Button-Stapling Machines, of which the following is a specification, reference being had therein to the accompanying drawings.

10 This invention relates to button attaching machines and has to do more particularly with the securing of buttons by improved means in a manner common to the earlier art. The advantages arising from the present 15 construction comprise convenient means for disconnecting the button-feed from the staple-forming and setting mechanism when it is desired to interrupt the securing of a given variety of buttons for the purpose of 20 substituting a single or small number of a different variety; improved means for suspending the feed-action of the stapling wire when, from any cause, a button is not in position to receive the wire through its shank; 25 effecting a rotary step-by-step movement of the button-carrier or wheel at both the effective and return movements of the means for positioning and securing the button; for controlling the gravity feed of the button 30 when entering the button-chute; for actuating and controlling the wire feeding mechanism and for dislodging the buttons from the button-chute when, for any purpose, it is desired to substitute a different variety, 35 together with strengthened and simplified means to better meet the requirements incident to machines of like build and comparatively rapid action.

It is to be understood that while the present 40 construction is herein shown and described as manually operated, as employed in shoe repair shops and by retail dealers generally, it is of simple mechanics to connect the operating rod with a power driven 45 rotary or oscillating crank member.

Referring to the figures which form a part of the specification, Figure 1 is a plan view of the present construction with the button receptacle cover turned back and 50 with the bracket-leaf carrying the stapling wire omitted. Fig. 2 is a view in front end elevation of Fig. 1. Fig. 3 is a view in rear end elevation of Fig. 2. Fig. 4 is a view in side elevation of Fig. 2 looking in 55 the direction indicated by the arrow *t*. Fig. 5 is a view in side elevation opposite to that

shown in Fig. 4. Figs. 6 and 7 are detailed views of the means employed for actuating the button-carrier or feed-wheel. Fig. 8 is a view in side elevation of the machine 60 frame, together with certain elements employed in forming and setting the button staples, said frame and elements being shown partly in section for a better understanding of the operative relationship of the 65 means above referred to. Fig. 9 is a view of the front end portion of the machine illustrating elements underlying certain elements illustrated in Fig. 11. Fig. 10 is a view in perspective of the staple setting 70 slide plate and the parts carried by the latter. Fig. 11 is a top view of certain parts overlying those illustrated in Fig. 9, later to be referred to. Fig. 12 is a view in perspective of a portion of the die- 75 bracket, together with the die. Fig. 13 is a view in elevation of the machine standard. Fig. 14 is a plan view of the latter figure. Fig. 15 is a view in perspective of the button receiving cup as when dislodging the 80 buttons from the button-chute for the purpose of substituting a different variety. Fig. 16 is a view in perspective of the staple setting plate, and Fig. 17 is a view of a 85 shoe-button with the staple inserted in the button-shank and showing in dotted lines the staple secured to the material.

Referring to the figures, 1 represents the machine standard base in which is suitably secured the lower end of the hollow standard 90 2 having suitably secured to its opposite end the table 3 and in said standard is mounted to move vertically an operating rod 4 pivotally connected at its lower end to an operating treadle 5 pivoted at 6 to a lug 7 95 forming a part of said base, and upon said standard is adjustably secured a lug 8 between which and said treadle is positioned a spring 9 acting to normally hold the treadle in its elevated position, as shown in 100 Fig. 13, said treadle being limited in its oppositely directed movements by the screws 10 and 11 threaded into suitable lugs carried by said base.

12 represents the machine frame provided 105 with the standards, as 13, 13, seated and secured upon the raised portion 14 of the table 3 by screws, as 15, 15, passing through openings, as 16, 16, formed in said raised portion and threaded into the respective standards. 110 17 denotes a triangularly shaped rock-lever housed in the machine frame and at one

corner suitably secured on the main rock-shaft 18 journaled in suitable bearings formed in said frame and to the corner 19 of said rock-lever is pivotally attached the 5 upper end of the operating rod 4, the corner 20 having pivotally attached to it a link 21 having its opposite end pivotally connected with the staple setting slide plate 22 mounted in suitable guideways, as 23, 23, 10 formed in the frame 12 and at its forward end provided with a suitably secured staple setting plate 24 having formed integral with it the staple setting prongs, as 25, 25, which, through the manual manipulation of the 15 treadle 5 and connections pointed out, cooperate with the die 26, having the concaved surfaces, as 26', 26', to clench the button securing staple, in a manner later to be described.

20 27 represents a wire cutting and bending bar held in sliding relationship with the slide-plate 22 by the guide-ribs, as 28, 28 formed on the staple setting plate 24, tracking the grooves, as 29, 29, formed in the inner walls of the wire cutting and bending elements 30, 30 of said bar 27, the latter being provided with suitably secured plates, as 30', 30', which, when moved downward, form an extension to the stationary chute, 25 later to be referred to, and serves as a guide to deliver the buttons from said stationary chute to the button registering head 39, the bar 27 being provided with wire receiving grooves, as 27', 27', a notch 31 and extension 32, the latter extending through a suitable opening 33 formed in a guide-plate 34 suitably secured to the slide-plate 22, a spring 35 carried by said extension acting to resiliently hold the bar 27 in its advanced position with respect to the slide-plate 22 except when the release pawl 36, carried by the latter, is automatically released from the notch 31, for a purpose later to be explained.

40 45 37 represents the button-registering lever fulcrumed to oscillate upon a shaft 38, journaled in suitable bearings provided in the frame 12. At its forward end the lever 37 is provided with a staple-forming and button-registering head 39, formed with a slot 40 having an end wall 41 for registering the shank of the button in position to receive the button-securing wire as it is passed from the supply 42. The slot 40 is formed with an 50 opening 43' acting as an outlet for any foreign substance which might interfere with the positioning of the buttons. In its passage from the supply 42, the wire passes through a bushing 43, thence through the shank of the button and abuts with its free 55 end against a stop 44, said stop 44 and bushing 43 being secured in the forward ends of guide-plates 45 and 46. The guide-plates 45 and 46 are secured by screws, as 47, to the frame 12. The head 39 is provided with a

slot 48 arranged transversely of the slot 40 to permit of a downward movement of said head, for a purpose hereinafter referred to.

To permit of the downward and effect an upward movement of the head 39, the lever 70 37 is provided with an elbow extension 49 the free end 50 of which bears against the under side of the slide-plate 22. The slide plate 22 is provided with an opening 51 into which said free end 50 projects through the 75 action of the incline 51' of the slide-plate 22 on the incline 51" of the lever 37 when the slide-plate is moved forward in the operation of the machine, the reverse movement of said slide causing the inclined wall 52 of 80 said opening to return said head to its effective or raised position. 53 denotes the die-bracket suitably secured to the front standard 13 of the frame 12, a cam-roller 54 carried by the release pawl 36 tracking the cam-slot 55 in the button feeding frame 56 suitably secured on the frame 12.

57 represents the button-carrier or feed-wheel suitably secured on the feed-shaft 58 journaled in suitable bearings formed in the 90 button-receptacle 59, said carrier being provided with button-carrying arms or ribs, as 60, between which the buttons lodge and are carried to the upper periphery of said carrier when owing to the inclines, as 61, they 95 are caused to fall into the button feeding chute 62 by which, through gravity action, they are directed into the button-chute 63 and along the edge of the inclined button-chute side guide-bar 65 to the action of the 100 spring depressed button-feed finger 66, said side guide-bar being removably secured to the frame 56 by a thumb-screw 67 and suitable dowel-pins, not shown. 68 denotes an oppositely arranged button-chute side guide-bar suitably secured to said frame and 105 69 the chute-cover-plate open at one side and having a groove 69' in its under side to permit of the passage of the buttons having a beaded or riveted shank at its upper side 110 (one variety being commercially known as the Morley button) as distinguished from a button having its shank molded in the button-head, as in Fig. 17, thus permitting of the securing of different varieties of buttons 115 without adjustment or change in the constructive elements, said cover-plate being secured by suitable dowel-pins, not shown, and screw 70, the latter passing through the guide-bar 68 and threaded into the frame 120 56. 71 denotes a spring depressed button-detaining finger hinged to the lower end of said chute-cover and provided with prongs, as 72, 72, for holding the buttons against feed-movements until the V-shaped notch 73 125 in the button feeding finger 66 is caused to engage the button and move it into the slot 40 of the head 39 with its shank in engagement with the wall 41.

74 represents a button agitating finger 130

suitably secured to the vertically arranged rock-shaft 75 journaled in the bearing 76 forming a part of the receptacle 59, the lower end of said rock-shaft carrying a 5 crank-arm 77 provided with a screw-pin 78 which at each backward movement of the slide-plate 22 is acted on by the plate 34 to rock said crank-arm and cause the finger 74 to agitate the buttons, and if the latter 10 are not in position to properly enter the chute 63 cause the same to be directed back into the receptacle, a suitably mounted spring 79 acting to reverse the movement of said crank-arm when said slide-plate is 15 moved forward. 80 denotes the button-receptacle cover plate hinged to a bracket 81 formed integral with said receptacle.

To give to the feed-wheel 57 the desired step-by-step rotary movements there is suitably secured on the shaft 58 a ratchet-wheel 82 and loosely mounted on said shaft are two disks 83 and 84 carrying spring depressed pawls 85 and 86 respectively, the disk 83 being connected with an oscillating 25 cam disk 87, carried by the main-shaft 18, by a link connection 88 and the disk 84 with said oscillating disk by a link connection 89, said pawls being pivotally secured on their respective disks and acting on the ratchet- 30 wheel to turn it in a single direction at each oppositely directed movement of said link connections, the movements of the latter being effected by the rocking movements of the main-shaft through the treadle and 35 treadle-connections previously pointed out.

90 denotes a two-ply disk mounted loosely on the shaft 58 and provided with peripheries of different radii and in each of said pawls are suitably secured pins, as 91, 91, 40 said two-ply disk being connected with the cover-plate 80 by a link 92 and when said plate is closed down upon the button-receptacle said pawl pins are caused to track directly over and in close proximity to the 45 smaller radii of the peripheries 93 and 94, but when the cover-plate is swung back the link 92 rotates said two-ply disk to a position to cause the pins to track the peripheries of said larger radii 95 and 96, thus 50 suspending the button-feed action of the feed-wheel while permitting the operation of all elements necessary to the securing of a button. 97 represents a bearing stud threaded into the frame 12, a split end 98 of 55 an arm 99 being suitably clamped upon a hub loosely journaled upon the stud 97 and integral with a button positioning lever 100 to which is pivotally connected the button-feed finger 66, the arm 99 being provided 60 with a cam-roller 101 tracking the periphery of the disk 87, the roller being held in contact with said periphery by a spring 102.

103 represents a wire-feed controlling arm fast on the rock-shaft 38 and having a de- 65 pending free end 104 normally in contact

with the button when in position to receive the fastening wire, the opposite end of said rock-shaft being provided with a suitably secured hub 105 having a lug 106 to the rear side of which is secured by screw 70 107 an arm 108 of the feed controlling latch-lever 109, the opposite side of said lug having secured to it an extension 110 the free end of which, in the operation of the machine is acted on by a cam-lug 111 carried 75 by the wire feed controlling disk 112 fast on the rock-shaft 18, the action of said cam-lug on said extension effecting an upward rocking movement of the levers 103 and 109, the return movements of which are controlled 80 by the spring 113 and when, from any cause, the button feeding mechanism fails in presenting a button to the action of the stalling mechanism the absence of the button from the registering head 39 permits the 85 free end of the lever 103 to rest on the latter and the lever 109 to rock the wire feed controlling latch 114 pivoted on the screw 115 and place the wall of its free end 116 in the path of movement of the wire feeding lever 90 117, thus suspending the feeding of the wire when the button is not in position to receive the latter.

118 represents the wire feeding cam loosely mounted on the main-shaft and provided with a cam portion 119 and actuated from the controller-disk 112 through the action of the end walls of the slot 120 on the stud-screw 121 threaded into said cam. The wire feeding lever 117 is pivoted on a 95 stud-bolt 122, depending from the bracket 123 suitably secured to the frame 12, and provided with a cam-roller 124, which, in practice, is acted on in opposition to the resiliency of the spring 125 by the cam portion 100 119, said spring acting on a rod 122' suitably mounted in lugs, as 123', 123', secured in the bracket-leaf 124', the inner end of said rod acting on a pin 125' carried by the lever 117 to return the latter to its feeding 105 position. 110

The lever 117 has suitably secured to its free end a wire feeding plate 126 on which is pivotally secured, by a screw 127, a toothed latch 128 resiliently held by the 115 suitably mounted spring 129 against accidental movement in a direction toward the button but movable in such direction when the lever 117 is moved in an opposite direction, it being understood that, as in the 120 earlier art, a movement of the lever 117 toward the button will cause the serrated free end of said latch to grip the wire between it and the stud 130 and feed the wire, and be free of such gripping action on said wire 125 when being moved in the opposite direction.

The means employed for holding the wire in its adjusted or forward position is the same as just described except that the plate 131, corresponding to the plate 126, is sta- 130

stationary and mounted on a bracket 132 suitably secured to the frame 12. The elements 112 and 118 coöperating to give to the wire a dwell sufficient to enable the shearing to 5 have taken place before the wire feed lever is returned which action insures the length of wire severed each time to be uniform.

133 denotes an indexing element carried by the head 39 the free end of which is located in alignment with the rib 134 formed by the intersecting walls of the concaved surfaces 26' of the die 26 and in a plane corresponding to the plane in which the slide-plate 22 moves, said element acting to indicate to the operator the correct locating of the shoe-button vamp with respect to the button to be secured. 136 denotes the button receiving cup for receiving the buttons when, for any purpose, it is desired to substitute a different variety of button.

The buttons are picked up by the button feed-wheel and deposited on the inclined button feeding chute 62 where they aline themselves with certain of the shanks depending within the groove and from the inclined chute the buttons are fed by gravity within the chute 63 from which they are transferred one at a time to the staple forming mechanism.

30 In the operation of setting a button pressure is applied to the treadle 5 which causes the lever 17 to be rocked thereby causing the slide-plate 22 to be moved forward carrying with it the wire cutting and bending bar 27, which latter in its forward movement severs the wire (which has previously been threaded through the button-shank), followed by bending the severed portion into U-shape around the button-registering head 39, when the release pawl 36, by the action of the cam-slot 55, is caused to be lifted out of engagement with the notch 31 in the bar 27 and simultaneously with this action the head 39 is lowered and withdrawn from the 45 wire staple and the slide continues its movement until the bar 27, carrying the staple in the grooves 29 contacts the shoe-upper, which has been previously placed over the die 26, when the continued movement of the slide 50 22 compresses the spring 35 and moves the bar 24 against the wire staple which forces the latter out of the grooves 29 and through the shoe upper into the curved recesses 26' of the die 26, thereby curling the ends of the 55 staples inwardly after passing through the shoe upper. As the pressure is removed from the treadle 5 the spring 9 causes the parts to be returned to retracted position, the actions taking place during this movement being as follows: The slide 22 on its return movement, through the action of the cam-surface 52 against the end 50 of the lever 37 causes its head 39 to be raised into position to receive the next subsequent button 60 which is placed thereon by the button 65

feed finger 66 when the bending bar 27 is again united to the slide 22 by the latch-lever 36 entering the notch 31 through the action of the cam-slot 55. The feed of the wire through the button-shank takes place 70 during the return movement of the slide 22, said wire feed movement commencing just as the head 39 has passed into position below the opening in the bushing 43.

The lost-motion provided between the disk 75 112 and feed-cam 118, which latter actuates the wire setting lever 117, through the slot 120 is for the purpose of preventing any withdrawal of the wire until the length of wire already fed to the button-shank has 80 been sheared off so that the length of wire sheared for each successive blank will always be the same.

The time of action of the button feeding finger 66 is such that it sets a button on the 85 head 39 immediately after the latter has been raised on the return movement of the slide 22. The action of the button feed finger in transferring buttons from the chute to the head 39 is as follows: The button positioning lever 100 is oscillated back-and-forth by the cam-disk 87 and spring 102 and as said lever approaches its retracted position the finger 66 is lifted on top of the button detaining finger 71 by riding the end 90 wall of the slot of the fork formed in the end of said latter finger, thereby permitting the lower-most button within the chute to fall in front of the notched end of the finger 66 in position to be engaged by the latter 95 during its downward movement and push the button out from under the finger 71. During the passage of the button from the chute to the head 39 the button-shank is guided between the inner edges of the plates 100 30' secured to and forming a part of the bar 27.

Having thus set forth the nature of the invention, what I claim herein is:—

1. In a staple-forming and button-secur- 110 ing machine, the combination with wire-feeding and -cutting, staple-forming and -securing and button-feeding means, of a wire-feed controlling arm independent of said button-feeding means yieldingly urged 115 to contact with a button positioned for reception of the wire, and a controlling latch adapted to be placed in the path of movement of said wire-feeding means by said controlling arms in the absence of a button. 120

2. In a staple-forming and button-secur- 125 ing machine, the combination with wire-feeding and -cutting, and staple-forming and securing means, of a button-feeding finger, means for actuating said finger to feed buttons into position to be threaded by the wire, a wire-fed controlling arm independent of said button-feeding finger adapted to contact with a button positioned for reception of the wire, means brought 130

into action by said arm in the absence of a button to arrest the effective action of said wire-feeding means, and means for retracting said controlling arm independently of 5 the buttons.

3. In a staple-forming and button-securing machine, the combination with wire-cutting, staple-forming and -securing and button-feeding means, of an actuating 10 shaft, an actuating element secured to said shaft, a cam-disk loosely journaled on said shaft and operatively connected with said actuating element, and spring-actuated wire-feeding means normally controlled by 15 said cam-disk to insure the severance of uniform lengths of wire by said wire-cutting means.

4. In a staple-forming and button-securing machine, the combination with wire-cutting, staple-forming and -securing and button-feeding means, of an actuating shaft, 20 an actuating element secured to said shaft, a cam-disk loosely journaled on said shaft and operatively connected with said actuating element, spring-actuated wire-feeding means normally controlled by said cam-disk, and means retracted by said actuating 25 element for arresting the effective action of

said wire-feeding means when from any cause a button is not in position to receive 30 the wire through its shank.

5. In a staple-forming and button-securing machine, the combination with wire-cutting, staple-forming and -securing and button-feeding means, of an actuating shaft, 35 an actuating element secured to said shaft, a cam-disk loosely journaled on said shaft and driven by said actuating element during a portion only of the movement of the latter, spring-actuated wire-feeding means 40 normally controlled by said cam-disk, a wire-feed arresting arm connected with said actuating element to be operated in one direction, and a spring adapted to actuate said arm in the opposite direction to arrest 45 the effective action of said wire-feeding means when from any cause a button is not in position to receive the wire through its shank.

In testimony whereof I have signed my 50 name to this specification, in the presence of two subscribing witnesses.

JOHN S. FINCH.

EDWARD H. WOODS,
FRANK M. WOOTTON.

Correction in Letters Patent No. 1,364,264.

It is hereby certified that in Letters Patent No. 1,364,264, granted January 4, 1921, upon the application of John S. Finch, of Bridgeport, Connecticut, for an improvement in "Button-Stapling Machines," an error appears requiring correction as follows: In the drawings, Sheet 1, for the signatures of inventor and attorney, which were omitted, read *Inventor John S. Finch, by F. W. Ostrom, Attorney*; and that the said Letters Patent should be read with this correction therein that the same may conform to the record of the case in the Patent Office.

Signed and sealed this 25th day of January, A. D., 1921.

[SEAL.]

L. B. MANN,
Acting Commissioner of Patents.
